UNITED STATES PATENT OFFICE.

GEORGE H. EVANS, OF OROVILLE, CALIFORNIA, ASSIGNOR TO THE RISDON IRON AND LOCOMOTIVE WORKS, OF SAN FRANCISCO, CALIFORNIA.

DESIGN FOR A NOZZLE FOR HYDRAULIC ELEVATORS.

SPECIFICATION forming part of Design No. 32,499, dated April 10, 1900.

Application filed March 14, 1900. Serial No. 8,675. Term of patent 14 years.

To all whom it may concern:

Be it known that I, GEORGE H. EVANS, a subject of the Queen of Great Britain, residing at Oroville, county of Butte, State of California, have invented and produced a new and original Design for a Nozzle for Hydraulic Elevators, of which the following is a specification, reference being had to the accompanying sheet of drawings, forming a part thereof, ²⁵ wherein—

Figure 1 is a perspective view of the nozzle. Fig. 2 is a top plan view of the nozzle; and Fig. 3 is a vertical sectional view taken on line xx , Fig. 2.

As shown in the drawings, the leading or material features of my design consist of the cone-shaped body portion A, having the verti-

cal wings or ribs A', and the reduced screw-threaded portion a, the inner wall B of the nozzle being gradually outwardly inclined or flared from point b to the lower edge of the screw-threaded reduced portion a.

Having thus described my invention, what I claim as new, and desire to secure by Letters Patent, is—

The design for a nozzle for hydraulic elevators, as herein shown and described.

In testimony whereof I affix my signature, in the presence of witnesses, this 19th day of January, 1900.

GEORGE H. EVANS.

In presence of—

N. A. ACKER,
D. B. RICHARDS.
